UNITED STATES PATENT OFFICE.

ELLIS H. MILLS, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 25, 1920. Serial No. 412,717.

To all whom it may concern:

Be it known that I, ELLIS H. MILLS, a citizen of the United States of America, residing at East Orange, in the county of 5 Essex, State of New Jersey, have invented certain new and useful Improvements in Telephone-Exchange Systems, of which the following is a full, clear, concise, and exact description.

10 This invention relates to a telephone exchange system and more particularly to a system in which the prepayment or registration of a toll is necessary before the desired connection can be fully established.

15 In systems of this character it is customary to provide the substation of a subscriber's line with a coin box and to effect the establishment of a desired connection by the deposit of a coin of the proper denomination 20 in the coin box. The coin box is provided with a magnet for causing the refunding or collection of the coin and with contact means operated by the deposit of the coin for connecting the magnet from one conductor of the subscriber's line to ground. Unscrupulous subscribers sometimes seek to evade payment by simulating the deposit of a coin through the connection of a ground 25 to the line, independently of the coin box.

30 It is, therefore, an object of this invention to provide means for preventing a subscriber from obtaining a desired connection except through the actual deposit of a coin in the coin box.

35 It is a further object of the invention to apply means for detecting a fraudulent operation of a subscriber's toll device to an automatic telephone system in such a manner that the calling subscriber may establish a desired connection to substantially its final switching stage before being required 40 to deposit a coin.

A feature of the present invention resides 45 in the employment of means for preventing the completion of a desired connection until after the deposit of the required coin, and further means comprising two marginal differential relays which, when operated by the proper deposit of a coin, render the preventing 50 means ineffective and which, when operated in a different manner by an attempt to simulate the deposit of a coin, have no effect upon the preventing means.

A further feature of the invention resides 55 in the employment of means as specifically

applied to a telephone system in which connections are established by automatic switching devices for preventing the establishment of a connection from progressing beyond a specified switching stage until after the actual deposit of the required coin in the coin box of the calling line. In systems of this character it is often desirable to permit a subscriber to entirely dial a desired number and to thereby initiate the selective operations at the central office before requiring him to deposit a coin, in order that the central station apparatus, after having been seized by the calling subscriber, may proceed without delay to extend the connection 70 towards the desired line.

Other features of the invention will be apparent as the description of the invention progresses. The invention will now be described in connection with the accompanying drawings in which—

Fig. 1 illustrates the invention as applied to a system in which connections are established by automatic switching devices; and

Fig. 2 illustrates the invention as applied to a system in which connections are established through the medium of an operator's manual circuit.

In Fig. 1 the switching devices have been diagrammatically represented by their respective switch brushes, and the central office switch controlling register-sender by the apparatus disclosed within the dotted rectangle, it being considered unnecessary to complete understanding of this invention to disclose in full the operating mechanism and circuits of the switches and the mechanism of the register-sender. The switches and sender may be of the type disclosed in the Patent No. 1,395,977, issued November 1, 1921, to F. A. Stearn and F. J. Scudder, and may function in the establishment of a connection in substantially the same manner as described therein. The sequence switch cams, associated with the district selector switch 20, are controlled by a sequence switch (not shown) associated therewith in the well-known manner. The sequence switch cams shown in the rectangle are controlled by a sequence switch (not shown) associated with the register-sender.

The invention will first be described in connection with the disclosure of Fig. 1, it being assumed that the calling subscriber A desires to establish a connection with the line 110

of subscriber B. To initiate the call the subscriber A removes his receiver from its switchhook and proceeds to operate the impulse dial S to dial the number of the desired line. Upon removing the receiver from the switchhook, the line switch 10 is operated in the well-known manner to extend the conductors of the calling line to the conductors 11 and 12 of a trunk circuit terminating in the district selector 20, and in the well-known manner the trunk conductors 11 and 12 are then extended through the upper contact of sequence switch cam 13, and the lower contact of sequence switch cam 14, to conductors 15 and 16 respectively, extending to the register-sending mechanism shown within the dotted rectangle through the normal contacts of relay 33.

In response to the operation of the impulse dial S, the registers of the register-sender are set in the well-known manner to register the code representing the office designation of the desired line and the number of the line in the desired office, and the sender then proceeds to set the district selector 20, the incoming selector 30, and the final selector 40 to extend the connection from trunk conductors 11 and 12 to the terminal of the desired line. The incoming selector 30 and the final selector 40 are controlled in the well-known manner over the fundamental circuit, which may be traced from trunk conductor 17, terminal 18 and brush 19 of the district selector 20, conductor 21, the right-hand contacts of sequence switch cam 22, conductor 23, the armature and back contact of O' counting relay 24, the windings of the sender stepping relay 25, the armature and back contact of relay 26, the right-hand contacts of sequence switch cam 27, trunk conductor 28, brush 29 and terminal 31 of the district selector 20, and thence to the trunk conductor 32. In the well-known manner, under the control of the registers of the sender and the counting relays, the incoming selector 30 is adjusted in its brush selection and group selection movements with the sequence switch of the sender in positions 6 and 8 respectively, and following the selective movements of the incoming selector switch the fundamental circuit is further extended to an idle final selector switch 40, which final selector switch is controlled in its brush selection and tens selection movements with the sequence switch of the sender in positions 10 and 12 respectively.

Following the completion of the tens selection movement of the final selector switch 40, the sequence switch of the sender advances out of position 12 and into position 14. If at this time the calling subscriber has not deposited a coin in the coin box of his substation, a circuit is established for relay 26, which may be traced from ground-

ed battery through the winding of relay 26, the contact of sequence switch cam 34, (13 to 14) and thence to ground through the armature and back contact of the differential marginal relay 35. Relay 26, upon 70 energizing, opens the fundamental circuit previously traced at its armature and back contact and therefore prevents the control of the final selector switch in its units selection movement, and the extension of the 75 connection is, therefore, arrested at this point of its progress until the subscriber has either deposited the required coin or abandons the call.

If the calling subscriber has deposited the 80 required coin prior to the advance of the sequence switch of the sender into position 13, then the differential marginal relay 35 is energized, thereby opening the circuit of relay 26, so that when the sender sequence 85 switch reaches position 14, the fundamental circuit, extending to the final selector switch, is closed and therefore effective for controlling the setting of the final selector switch upon the terminals of the desired 90 line. The circuit for relay 35 may be traced from grounded battery through the right-hand winding of relay 35, the right-hand winding of differential marginal relay 36, the outer armature and front contact of relay 33, which is energized following the completion of registration of the call at the sender, conductor 15, the upper contact of sequence switch cam 13, conductor 11, the upper bank terminal and brush of line 100 switch 10, the winding of the coin box magnet 37, which is of approximately 1000 ohms resistance and thence to ground through contacts 38, which were permitted to close when the calling subscriber deposited the coin. 105 The current flowing in this circuit, while sufficient to energize relay 35, is not sufficient to energize relay 36, and therefore the circuit previously traced for relay 26 is opened at the armature and back contact of relay 35. Relays 35 and 36, being differentially wound, do not energize in the series circuit, which may be traced from grounded battery through the right-hand windings of 110 these relays, the outer armature and front contact of relay 33, conductor 15 the upper contact of sequence switch cam 13, thence over the subscriber's line and back through the lower contact of sequence switch cam 14, conductor 16, the inner armature and front contact of relay 33 and to ground through the left-hand windings of relay 36 and 35. 115

If the calling subscriber attempts to simulate the deposit of a coin by directly grounding the tip conductor of his line at the substation, independently of the ground through the winding of the coin box magnet 37, then sufficient current flows through the right-hand windings of relays 36 and 35 to energize both of these relays. Relay 35, 120 125 130

upon energizing, opens the circuit of relay 26, but since at this time relay 36 is also energized, the circuit of relay 26 is effectively closed at the armature and front contact of relay 36 when the sender sequence switch closes the contact of cam 34 upon reaching position 13, and thus the progress of the connection is arrested immediately prior to units selection, in the same manner as when 10 the calling subscriber failed to deposit the required coin.

On party lines the bells at the subscriber's stations are customarily connected, some to the tip conductor of the line, and others to the ring conductor of the line, through the normally closed contacts of the switchhooks at the several stations. The grounded bell conductor therefore extends to the desk set through the extension cord together with 20 the tip and ring talking conductors. Should a subscriber endeavor to simulate the deposit of a coin by puncturing the extension cord with a pin or other sharp instrument for the purpose of connecting the bell ground 25 to either the tip or ring conductor, then owing to the high resistance of the bell ground which is approximately 4000 ohms, insufficient current flows through the windings of relays 36 and 35 to energize them 30 since relay 36 is designed to energize only upon the connection of a direct ground at the subscriber's substation, and relay 35 is designed to operate only when the resistance of its external circuit is less than 3800 35 ohms. Since neither relay 35 nor 36 is energized the same condition prevails as when the subscriber deposits no coin, and the progress of the call is arrested.

Following the successful extension of the 40 connection to the terminals of the desired line B, the sequence switch of the district selector 20 is advanced out of position 10, in the well-known manner, and into position 14, in which position the calling subscriber's line A is connected for conversation 45 with the subscriber's line B. Talking current is supplied to the subscribers' lines, in the well-known manner, and the collection of the coin deposited in the coin box of the 50 calling line is made in the usual manner by the energization of magnet 37 upon the termination of the conversation after the calling subscriber has restored his receiver to the switchhook. For coin collection circuits functioning in this manner, reference 55 may be had to Patent 1,332,922, issued March 2, 1920, to A. E. Lundell and George Thompson.

In Fig. 2 the invention has been disclosed 60 in connection with manual circuits. It will be assumed that the subscriber at substation C desires to obtain a connection with a subscriber at substation D, and to initiate the call removes his receiver from the switchhook. Upon the removal of the receiver

from the switchhook a circuit is established for the line relay 67, which may be traced from grounded battery through the right-hand winding of relay 67, the right-hand armature and back contact of cutoff relay 68, thence over the subscriber's line loop, and back through the left-hand armature and back contact of relay 68 to ground through the left-hand winding of line relay 67. Relay 67, energizing in this circuit, 70 establishes a circuit for the line lamp 39.

The operator, upon noting the illumination of the line lamp 39, picks up the answering plug P of an idle cord circuit O at her position and inserts it in the jack J of the calling line. A circuit is now established from battery through the coin test lamp 41, the normally closed make-before-break contacts of the inner left-hand armature of relay 42, the sleeve contact 43 of the plug P, the sleeve contact 44 of the jack J, and thence to ground through the winding of cutoff relay 68. Lamp 41 is illuminated in this circuit and relay 68 energizes. The energization of relay 68 opens, 80 at its armatures and back contacts, the circuit previously traced for line relay 67, thereby extinguishing the line lamp 39. 90

The operator now depresses the listening key 45 to connect her head set indicated at 95 OT to the subscriber's line over the contacts of the keys 55 and 56 and the tip and ring contacts of the plug P and jack J, and obtains from the calling subscriber the number of the line desired. In response to the 100 instructions received from the calling subscriber, the operator then tests the multiple terminal of the desired line in the usual manner to determine its free or busy condition, and if found free inserts the calling 105 plug P' of the cord circuit O in the jack J' of the desired line D.

Upon the insertion of the plug P' in the jack J', a circuit is established from grounded battery through the supervisory lamp 46, the sleeve contact 47 of the plug P', sleeve contact 48 of jack J', and thence to ground through the cutoff relay 49 of the desired line. The lamp 46 becomes illuminated and remains illuminated until the called subscriber responds to the application of ringing current, which the operator applies to the called line in the well-known manner. When the called subscriber responds, the supervisory relay 50 becomes energized over 110 the called subscriber's line loop in the well-known manner, closing, at its armature and front contact, a shunt around the supervisory signal lamp 46 effacing the signal. 115

Upon the successful extension of the connection to the desired line, the operator again depresses the listening key 45 and instructs the calling subscriber to deposit the required coin. The operator then releases the key 45. When the calling sub- 120 125 130

scriber in response to the instructions of the operator deposits the required coin in the coin box, the contacts 51 at the coin box are closed to connect the windings of the 5 coin box magnet 52 from ground to the tip conductor of the calling subscriber's line. A circuit is now established from grounded battery through the right-hand winding of the differential marginal relay 53, the 10 right-hand winding of the differential marginal relay 54, the right-hand armature and back contact of relay 42, the upper normally closed contact of listening-in key 45, the upper normally closed contact of the coin collect 15 key 55, the upper normally closed contact of the coin refunding key 56, the tip contacts of plug P and jack J, the tip conductor of the calling subscriber's line, and thence to ground through the windings of magnet 52 and 20 contacts 51. Due to the resistance of the coin box magnet 52, marginal relay 54 does not energize in this circuit. Marginal relay 53 becomes energized. A circuit is therefore established for relay 42, which 25 may be traced from grounded battery through the right-hand winding of relay 42, the armature and back contact of relay 54, and thence to ground through the armature and front contact of relay 53. Relay 42, upon energizing, closes a locking circuit for itself which may be traced from grounded battery through the winding of supervisory signal lamp 57, conductor 58, the left-hand winding of relay 42, the make 30 contacts of the inner left-hand armature of relay 42, sleeve contact 43 of the plug P, sleeve contact 44 of the jack J, and thence to ground through the winding of cutoff relay 68. At its right-hand armature and 35 back contact and outer left-hand armature and back contact, relay 42 opens the circuit extending through the windings of relays 53 and 54, and at the front contacts of these armatures extends the tip and ring conductors of the answering end of the cord circuit from the plug P to the left-hand windings of the repeating coil 59. At its inner 40 left-hand armature relay 42 opens the circuit previously traced through the coin test lamp 41, thereby extinguishing the lamp to signify to the operator that a coin has been deposited in the proper manner. Supervisory signal lamp 57 does not become illuminated in the circuit previously traced 45 through the left-hand winding of relay 42, since upon the energization of relay 42 and the connection of the answering strands of the cord circuit to the left-hand windings of repeating coil 59, the answering supervisory relay 60 becomes energized over the 50 calling subscriber's line loop, and at its left-hand armature and front contact closes a shunt around the supervisory signal lamp 57. 55 Due to the fact that relays 53 and 54 are

differentially wound, these relays do not become energized when connected through the right-hand armature and back contact and outer left-hand armature and back contact of relay 42, and thence over the 70 calling subscriber's line loop, but energize only when a ground is connected to the tip conductor of the calling line. Following the termination of the conversation between subscriber C and subscriber D, the 75 subscribers restore their receivers to their switchhooks, thereby opening the circuits of supervisory relays 60 and 50, causing the illumination of supervisory signal lamps 57 and 46 in the well-known manner. 80 The operator then proceeds to take down the connection, whereupon all apparatus employed in the establishment of the connection is restored to normal condition.

If the calling subscriber, through the 85 fraudulent connection of a direct ground to the tip conductor of his line, attempts to obtain a completed connection without the proper deposit of a coin in the coin box, his act is detected in the following manner: Upon the connection of the direct ground to the tip conductor of the calling line, a circuit is established from grounded battery through the right-hand windings of relays 53 and 54, the right-hand armature 90 and back contact of relay 42, and thence as previously traced over the tip conductor of the calling line and to ground directly through the fraudulent ground connection. Since the ground connection is of much 100 lower resistance than the connection through the windings of the coin box magnet 52, both marginal relays 53 and 54 now become energized, and although relay 53 attracts its armature to establish a connection through the right-hand winding of relay 42, relay 54 breaks this established connection at its armature and back contact and therefore relay 42 does not energize, and therefore the coin test lamp 41 remains 105 illuminated to signify to the operator that the calling subscriber has not yet deposited the required coin. Since relay 42 is not energized, the talking circuit between the calling subscriber's line and the called subscriber's line remains open at the contacts of this relay.

If the operator desires to give the calling subscriber a free connection to the line desired, the operator depresses the coin refunding key 56, which, at its lowermost contact, closes a circuit from grounded battery through the right-hand winding of relay 42, thence over conductor 61 to ground at the contact of key 56. Relay 42 becomes 120 energized and, in the manner previously described, causes the closure of the tip and ring conductors of the cord circuit, thereby permitting communication between the calling and called subscribers. If at any time 125

130

prior to the energization of relay 42 the operator wishes to converse with the called subscriber, the operator depresses key 62, which connects her head set to the calling 5 strands of the cord circuit and thereby to the called subscriber's line.

While the invention has been disclosed in both modifications as employed with subscribers' lines having coin boxes, it is to be 10 understood that the invention is equally applicable for use with subscribers' lines provided with toll charging apparatus, as, for example, message registration apparatus.

What is claimed is:

15 1. In a telephone exchange system, a central office, a calling line, a called line, means at said central office for extending a connection between said lines, a charging device on said calling line, means at said central office for arresting the completion of said connection until after the operation of said charging device, and means comprising a plurality of marginal differential relays for rendering said arresting means ineffective.

20 2. In a telephone exchange system, a central office, a calling line, a called line, means at said central office for extending a connection between said lines, a charging device on said calling line, a relay at said central office for arresting the completion of said connection until after the operation of said charging device, and means comprising a plurality of marginal differential relays under the control of said charging device for controlling said first relay to effect the completion of said connection.

25 3. In a telephone exchange system, a central office, a calling line, a called line, means at said central office for extending a connection between said lines, a toll device on said calling line, a relay at said central office for arresting the completion of said connection until after the operation of said toll device, a pair of marginal differential relays under the control of said calling line, and a circuit for said first relay extending through contacts of said latter relays for effecting the operation of said first relay to complete said connection upon the proper operation of said toll device.

40 4. In a telephone exchange system, a central office, a calling line, a called line, means at said central office for extending a connection between said lines, a toll device on said calling line, a relay at said central office for arresting the completion of said connection until after the operation of said toll device, a pair of marginal differential relays under the control of said calling line, and a circuit for said first relay extending through contacts of said latter relays, said circuit being rendered effective to control said first relay to complete said connection upon the operation of one of said latter re-

lays when said toll device is properly operated and rendered ineffective upon the operation of the other of said relays upon an attempt to simulate the operation of said toll device.

70

5. In a telephone exchange system, a central office, a calling line, a called line, means at said central office for extending a connection between said lines, a toll device on said calling line, a relay at said central office for arresting the completion of said connection until after the operation of said toll device, a pair of marginal differential relays under the control of said calling line, and a circuit for said first relay extending through contacts of said latter relays, said circuit being rendered effective to control said first relay to complete said connection upon the operation of one of said latter relays when said toll device is properly operated and rendered ineffective upon failure of said latter relays to operate upon an attempt to simulate the operation of said toll device by the connection of a high resistance ground to either of the conductors of said calling line.

80

6. In a telephone exchange system, a central office, a calling line, a called line, means at said central office for extending a connection between said lines, a coin collecting device on said calling line, a relay at said central office for arresting the completion of said connection until after the operation of said device, a pair of marginal differential relays under the control of said calling line, both of said relays being responsive to a direct ground connection upon one conductor of said calling line and one only of said relays being responsive to a high resistance ground connection on said conductor, and a circuit for said first relay extending through contacts of said latter relays, said circuit being rendered effective to control said relay to complete said connection upon the connection of a resistance ground to said conductor through the deposit of a coin in said coin device and rendered ineffective upon the connection of a direct ground to said conductor upon an attempt to simulate the deposit of a coin.

95

7. In a telephone exchange system, a calling line, a called line, selector switches for extending a connection between said lines, a charging device on said calling line, means for arresting the operation of one of said switches to complete said connection until after the operation of said charging device, and means comprising a plurality of marginal relays for rendering said arresting means ineffective.

100

8. In a telephone exchange system, a calling line, a called line, selector switches comprising a final selector switch having access to the terminal of said called line for extending a connection between said lines, a

130

charging device on said calling line, means for arresting the operation of said final selector switch until after the operation of said charging device, and means comprising a plurality of marginal differential relays for rendering said arresting means ineffective.

9. In a telephone exchange system, a calling line, a called line, selector switches operable in a plurality of switching stages to extend a connection between said lines, a charging device on said calling line, means for arresting the progress of said connection through said switching stages immediately prior to the last of said switching stages and until after the operation of said charging device, and means controlled by the operation of said device for rendering said arresting means ineffective whereby said arrested connection becomes completed.

10. In a telephone exchange system, a calling line, a called line, selector switches operable in a plurality of switching stages to extend a connection between said lines, a sending mechanism for controlling said switches, a charging device on said calling line, means for arresting the operation of said sending mechanism immediately prior to the control of said switches in the last of said switching stages and until after the operation of said charging device, and means controlled by the operation of said device for rendering said arresting means ineffective.

11. In a telephone exchange system, a calling line, a called line, selector switches operable in a plurality of switching stages to extend a connection between said lines, a sending mechanism, a control circuit extending between said mechanism and said switches, a charging device on said calling line, means for opening said control circuit immediately prior to the operation of said sending mechanism for controlling said selector switches in the last of said switching stages and until after the operation of said charging device, and means controlled by the operation of said device for rendering said arresting means ineffective.

12. In a telephone exchange system, a calling line, a called line, selector switches operable in a plurality of switching stages to extend a connection between said lines, a sending mechanism, a control circuit extending between said mechanism and said switches, a charging device on said calling line, a relay for opening said control circuit immediately prior to the operation of said sending mechanism for controlling said selector switches in the last of said switching stages and until after the operation of said charging device, and a plurality of marginal differential relays under the control of said calling line for controlling said relay.

13. In a telephone exchange system, a calling line, a called line, selector switches operable in a plurality of switching stages to extend a connection between said lines, a sending mechanism, a control circuit extending between said mechanism and said switches, a toll device on said calling line, a relay for opening said control circuit immediately prior to the operation of said sending mechanism for controlling said selector switches in the last of said switching stages and until after the operation of said toll device, a pair of marginal differential relays under the control of said calling line, and a circuit for said first relay extending through contacts of said latter relays, said circuit being rendered ineffective to operate said first relay upon the operation of one of said latter relays when said toll device is properly operated and rendered effective to operate said relay upon the operation of the other of said relays upon an attempt to simulate the operation of said toll device.

14. In a telephone exchange system, a calling line, a called line, numerical selector switches operable in a plurality of switching stages to extend a connection between said lines, a charging device on said calling line, means for arresting the progress of said connection through said switching stages subsequent to the establishment of said connection through certain of said stages and prior to its establishment through all of said stages and until after the operation of said charging device, and means controlled by the operation of said device for rendering said arresting means ineffective whereby said arrested connection becomes completed.

15. In a telephone exchange system, a calling line, a called line, selector switches operable in a plurality of switching stages to extend a connection between said lines, a sending mechanism for controlling said switches, a charging device on said calling line, means for arresting the operation of said sending mechanism subsequent to the establishment of said selection through certain of said stages and prior to its establishment through all of said stages and until after the operation of said charging device, and means controlled by the operation of said device for rendering said arresting means ineffective whereby said arrested connection becomes completed.

16. In a telephone system, a subscriber's line extending to a central office, coin collecting mechanism at the station on said line, automatic selector mechanism at the exchange controllable from said station only after a coin has been deposited in said coin mechanism, means at said exchange responsive to the deposit of a coin for rendering said selector mechanism controllable, and other selector mechanism at the exchange

controllable from said station without depositing a coin.

17. In a telephone exchange system, a central office, a calling line, a called line, means at said central office for extending a connection between said lines, a charging device on said calling line, means for arresting the completion of said connection until

after the operation of said charging device, and means comprising a plurality of marginal differential relays for rendering said arresting means ineffective. 10

In witness whereof, I hereunto subscribe my name this 22nd day of September A. D., 1920.

ELLIS H. MILLS.
